United States Patent Office

Des. 193,706
Patented Oct. 2, 1962

193,706

GOCART

John W. Davies, Plymouth, Wis., assignor to Gilson Bros.
Co., Plymouth, Wis., a corporation of Wisconsin

Filed May 11, 1961, Ser. No. 65,122

Term of patent 14 years

(Cl. D14—3)

Fig. 4

Fig. 5

Fig. 6

FIG. 1 is a side elevation of a gocart embodying my new design.

FIG. 2 is a plan view thereof.

FIG. 3 is a perspective view thereof.

FIG. 4 is a front view thereof, with portions omitted for clarity of illustration.

FIG. 5 is a rear view thereof.

FIG. 6 is a perspective view of the body portion of the gocart shown in FIG. 1 with portions omitted for clarity of illustration.

I claim:

The ornamental design for a gocart, as shown and described.
